FEED WATER HEATER OF THE INJECTOR
TYPEHarry Edward Gresham and James Neville
Gresham, Salford, Manchester, EnglandApplication July 11, 1931, Serial No. 550,182, and
in Great Britain April 14, 1931

4 Claims. (Cl. 122—442)

This invention relates to feed water heaters of the injector type. With such heaters, it is found that owing to the high temperature of the feed water in the heater, deposits of hardness salts 5 from the feed water tend to occur very rapidly in the heater, such salts adhering tenaciously to the cones and quickly restricting their bore.

The object of our present invention is to provide an improved construction of heater in which 10 the whole of the cones can be readily removed as a single unit without breaking any pipe joints, so that the substitution of a new unit can be made expeditiously. A further object of our invention is to provide a construction of heater in which all 15 the cones are held in their correct relative positions without the use of screwed joints.

A heater in accordance with our invention comprises a unitary structure consisting of inlet, intermediate and delivery cones held together without 20 screwed joints and secured in position by a cap in the heater casing, the removal of said cap permitting of the removal of the unitary structure by a plain axial movement.

Referring to the accompanying explanatory 25 drawings:—

Figure 1 is a sectional elevation and Figure 2 a plan view of one form of feed water heater constructed in accordance with our invention.

Figure 3 is a sectional elevation and Figure 4 30 an end elevation looking from the left of Figure 3, of a modified construction of feed water heater in accordance with our invention.

The same reference letters in the different views indicate the same or similar parts.

35 In Figures 1 and 2, the heater proper is adapted to be inserted directly into a boiler, part of the shell of which is indicated at *a*. The part external to the boiler is flanged at *b* for attachment to the boiler and has a side connection *c* leading 40 from the injector (not shown) which delivers the feed water to the heater. Such connection may, if desired, have a stop and or feed check valve *d* thereon. The final or delivery cone *e* of the heater is combined with a ported cylinder 45 *f* with an internal seating *g*, upon which rests the intermediate cone *h* which is held in position by projections *i* from the inlet cone *j* which is itself secured to the end of the cylindrical extension *f* of the delivery cone *e* by studs *k*

50 passing through a flange upon the inlet cone and through a flange *m* upon a portion of a head piece *n* which has apertures *o* therein for the inflow of the feed water to the inlet cone *j*, and a tapped aperture *p* in its end face into which an eye bolt or the like can be secured to facilitate the axial withdrawal of the cones as a unitary structure from the heater. A cap *q* screws into the end of the heater casing and bears upon said head piece *n* to hold the structure in position, 55 when an external shoulder *r* upon the cylindrical

extension *f* of the delivery cone *e* seats upon an internal shoulder in the flanged part of the heater casing.

Steam from the boiler enters the heater through the ports *t* to pass into the water jet issuing from the cone *j*. Further steam enters through the ports *u* to pass into the water jet between the intermediate cone *h* and the delivery cone or nozzle *e*. The latter cone or nozzle delivers the heated feed water laterally as shown by the arrow *v*, Figure 2.

A stop pin or stud *w* engages a hole or slot in the head piece *n* for the purpose of preventing rotary movement of the heater cones and to ensure correct setting in the boiler.

It will be seen that if the cap *q* is removed and an eye bolt or the like be screwed into the hole *p*, the whole of the heater parts (that is the nozzle *e* and its cylindrical extension *f*, the cones *h* and *j* and the head piece *n*) can be withdrawn 80 as a single unit and then by releasing the screwed studs *k*, the cones *j* and *h* can be withdrawn for descaling or cleaning purposes. There is then a clear passage way for scaling or cleaning the nozzle *e*.

Instead of arranging the heater with the cones within the boiler steam space, it may as shown in Figures 3 and 4, be arranged entirely on the exterior of the boiler, the flange *b* upon the heater by which it is secured to the boiler having 90 therein a steam inlet port or branch *x* and a feed outlet branch *y*. There is a cap *z* at the delivery end of the heater casing; by the removal of the caps *z* and *q* at both ends of the heater, complete access to the casing is available 95 for cleaning purposes.

With our construction, it is unnecessary to break any pipe joints in order to remove all the cones of the heater for cleaning or renewal. As the cones fit together without screwing, they 100 can even though heavily coated with scale be readily taken apart.

It will be appreciated that the invention is not concerned with a construction in which the nozzles are formed as a unit structure as such a 105 construction would not fulfill the objects of the invention; neither is the invention concerned with a nozzle structure which is screw threaded into the heater casing.

What we claim is:

1. A feed water heater of the injector type comprising in combination a heater casing having an internal shoulder therein, a delivery cone having a cylindrical extension provided with an internal seat and an external shoulder seated 115 upon said internal shoulder and also with ports for communication with a source of steam, an intermediate cone within said cylindrical extension resting upon said internal seat, an inlet cone within and secured to said cylindrical ex- 120

tension adjacent said external shoulder to hold said intermediate cone upon said internal seat, and means associated with said heater casing to maintain said cylindrical extension with its 5 external shoulder upon said internal shoulder.

2. A feed water heater of the injector type comprising in combination a heater casing having an internal shoulder therein, a delivery cone having a cylindrical extension provided with an 10 internal seat and an external shoulder seated upon said internal shoulder and also with ports for communication with a source of steam, an intermediate cone within said cylindrical extension resting upon said internal seat, an inlet cone within and secured to said cylindrical extension adjacent said external shoulder and having longitudinal projections engaging with said intermediate cone to hold said intermediate cone upon said internal seat, a head piece with- 15 in said heater casing, and a cap screwed into said heater casing to bear upon said head piece to maintain said cylindrical extension with its external shoulder upon said internal shoulder.

3. A feed water heater of the injector type comprising in combination a heater casing having an internal shoulder therein and a branch for connection to a boiler feed pipe, a delivery cone having a cylindrical extension provided with an internal seat and an external shoulder seated upon said internal shoulder and also with ports for communication with a source of steam, an intermediate cone within said cylindrical extension resting upon said internal seat, an inlet cone within said cylindrical extension and hav- 20 ing a flange seated upon said cylindrical extension adjacent said external shoulder, a flanged head piece within said heater casing with its flange adjacent the flange of said inlet cone, studs passing through said flanges and into said

cylindrical extension to hold said head piece, inlet cone, intermediate cone and delivery cone together as a unit structure, and a cap screwed into said heater casing to bear upon said head piece to maintain said cylindrical extension with its external shoulder upon said internal shoulder and removable to permit the removal of said unit structure by a plain axial movement.

4. A feed water heater of the injector type comprising in combination a heater casing having an internal shoulder therein and a branch for connection to a boiler feed pipe, a delivery cone having a cylindrical extension provided with an internal seat and an external shoulder seated upon said internal shoulder and also with ports for communication with a source of steam, an intermediate cone within said cylindrical extension resting upon said internal seat, an inlet cone within said cylindrical extension and having a flange seated upon said cylindrical extension adjacent said external shoulder, a flanged head piece having an aperture in its outer end face disposed within said heater casing with its flange adjacent the flange of said inlet cone and ported for the entry of the feed water op- 100 posite said branch, studs passing through said flanges and into said cylindrical extension to hold said head piece, inlet cone, and delivery cone together as a unit structure, and a cap screwed into said heater casing to bear upon said 105 head piece to maintain said cylindrical extension with its external shoulder upon said internal shoulder and removable to permit the insertion of a member into said aperture for the removal of said unit structure by a plain axial move- 110 ment.
